Inventor

William H. Eggars.

By his Attorney,

W. R. Hutchinson.

UNITED STATES PATENT OFFICE.

WILLIAM H. EGGERS, OF BROOKLYN, NEW YORK.

RADIO TUBE SOCKET.

Application filed June 5, 1925. Serial No. 35,211.

My invention relates to improvements in sockets such as are used for holding radio tubes in radio receiving apparatus. As generally arranged, these tubes which are rather expensive, support the internal elements, to wit, the filament, grid, and plate, in such a way that it often happens that some of the elements or their connections are disturbed or broken so as to ruin the working of the tube, and as the tubes are expensive it is quite a serious matter. I am aware that attempts have been made to obviate this by cushioning the whole support which carries the set, but this does not accomplish the desired result. My invention is intended to produce a simple socket in which the body portion which receives the tube, is cushioned on its base in such a manner as to afford practically a shock absorber against movement either toward or away from the base, thereby rendering the socket a very safe support for its tube, and preventing likelihood of accidental disruption of the tube elements or their connections.

My invention also is intended to provide terminals for the tube elements which are supported in such a way that they are not likely to be disarranged, have straight essentially radial lines, and are spaced from one another in such a manner as to afford the least possible loss by induction or the like. The invention is also intended to produce a structure which affords a safe and economical support for the tube and its elements, and which can be easily and economically made. All of which will be better understood from the following description.

Reference is to be had to the accompanying drawings forming a part of this specification, in which similar reference characters indicate corresponding parts in all the views.

Figure 1 is a side elevation of the tube socket embodying my invention.

Figure 2 is a broken plan view thereof.

Figure 3 is a side elevation of the body of the socket removed from its base, and

Figure 4 is an enlarged detail perspective of one of the terminals or contact arm.

The socket is provided with a base 10 which is flat, and preferably though not necessarily rectangular, this being of insulating material, and having preferably perforated feet 11 to facilitate its attachment to a support. The base is adapted to yieldingly support the tubular body 12 and yet

hold the same firmly and in position to receive the conventional tube in the usual manner. In the drawings the tube is indicated by dotted lines. The body 12 is substantially as usual, having a bayonet slot 13 to connect with the tube, but at the bottom it varies from the usual body in that it has laterally extending lugs or ears 14 which are regularly spaced around the outside of the body, and which are preferably, though not necessarily, four in number. These ears 14 are adapted to seat on a cushion 15 resting on the base 10, the cushion being preferably of rubber, and in the form of a washer, while above each ear is a second rubber cushion 16, and a fastening such as a screw bolt 17 extends through the base, both cushions, and each ear 14, as shown in Figure 1, and a nut 18 serves to fasten the parts together. Obviously springs might be substituted for the parts 15 and 16, but they would not be nearly as suitable as soft sponge rubber. As the ears and connected parts are spaced around the tubular body as shown, and the nuts 18 can be tightened to the necessary extent, just the desired amount of elasticity can be had and yet the connection will be firm.

The base 10 is provided with countersunk seats 20 which are spaced between the ears 14 and their connections, as shown in Figure 2. These seats are perforated as at 21 and receive the base flange 22 of a contact or terminal 23 which is preferably a flat connector, and extends substantially parallel with the base. The body portion 23 connects with the flange 22 as shown at 24, and the parts 23 and 22 are perforated as at 25 and 26 to receive the fastening binding screw 30, presently referred to.

The inner end of each terminal 23 is preferably bent at right angles as at 27', and formed into a socket 27 made by turning up the flanges 28, this being adapted to connect as usual with the elements of the tube which are not here shown as they form no part of this invention.

A bearing washer 31 is arranged between the parts 22 and 23 of each terminal, and through this extends the binding screw 30, which has the usual nut 31. To provide for freedom of movement and prevent any possible interference, the tubular body 12 is cut away at intervals in the lower edge as shown at 29, and through these cut away spaces the terminals 23 extend.

By reference to the drawings it will be

2

seen that the terminals 23 are anchored in such a way that there is little likelihood of their being disturbed, that they extend straight into the tubular body 12, and that by the radial arrangement shown they are as far from each other as possible. It will further be seen that I provide a very firm yet cushioned connection between the member 12 and the base 10, and that the cushion 5 is double-acting, the down thrust being absorbed by the cushions 15 and the up thrust by the cushions 16, either of which can be made of suitable material and of desired thickness or resilience. Thus I have provided a very simple inexpensive tube socket which will receive the conventional tube and connect with its elements in the conventional manner, and which will afford a very safe support adapted to hold the tube securely.

10 I claim:—

1. A radio tube socket comprising a base having a plurality of substantially equidistantly countersunk seats, a tubular body provided with a plurality of cut-away portions 15 on its lower edge corresponding to said countersunk seats, a terminal secured at one end in each of said seats and having the other end thereof overlapped and extending into the tubular body through the cut-away portions therein, a plurality of outwardly

extending ears on the tubular body near the lower edge thereof and adjacent said cut-away portions, means extending through said ear and base for connecting said tubular body and said base with the cut-away 35 portions in alignment with the countersunk seats, and a cushioning element above and below each ear and retained by said connecting means.

2. A radio tube socket comprising a base, 40 a tubular body serving as a tube socket, said body being disposed above the base and having symmetrically arranged external ears near the bottom, and with openings through the wall between the ears, cushions between 45 the base and the ears and also above the ears, means extending through the cushions and ears and connecting with the base, said means serving also to tension the cushions on the ears, and flat spring contact arms supported on the base and extending through the openings in the tubular body, said arms being symmetrically spaced apart and having their inner ends bent laterally and provided with terminal sockets adapted to connect with tube elements. 50

In testimony whereof, I have signed my name to this specification this 3 day of June, 1925.

WILLIAM H. EGGERS.
